UNITED STATES PATENT OFFICE.

ALBERT WADKINS HARVEY, OF ROCKWALL, TEXAS.

STOCK-FEEDING DEVICE.

No. 841,864.

Specification of Letters Patent.

Patented Jan. 22, 1907.

Application filed October 13, 1906. Serial No. 338,761.

To all whom it may concern:

Be it known that I, ALBERT WADKINS HARVEY, a citizen of the United States, residing at Rockwall, in the county of Rockwall and State of Texas, have invented new and useful Improvements in Stock-Feeding Devices, of which the following is a specification.

This invention is a stock-feeding device, and more particularly that kind in which the feed is stored in a bin located above the feed-trough and from which it is dumped by means which are operated from a distance.

The object of the invention is to provide a simple and easily-operated device of this kind; and to this end the invention consists of a construction and arrangement of parts hereinafter described and claimed.

In the accompanying drawings, Figure 1 is a front elevation of the invention. Fig. 2 is a plan view. Fig. 3 is a transverse section on the line 3 3 of Fig. 2.

Referring specifically to the drawings, 5 denotes a bin, having hangers 6, whereby it is suspended in a suitable manner above a feed-trough or manger. The bin has partitions 7, forming compartments to receive different kinds of feed. The bottom 9 of the bin is hinged at 10 to swing downwardly and release the feed.

To the rear wall 11 of the bin, on the inside thereof, is pivoted, as at 12, a latch 13, having a notch 14 to receive a pin 15, extending from the free edge of the bottom 9, whereby said bottom is held closed. When the latch is swung on its pivot to release the pin 15, the bottom drops down and allows the feed to drop into the feed-trough or manger. The free edge of the bottom is recessed, as at 16, to form a space for the lower end of the latch to work in. An operating-rope 17 is made

fast to one end of the latch, and the other end of the rope extends to any desired place—as, for instance, the dwelling of the proprietor—so that the stock can be fed without leaving 45 the house and going to the barn. A number of feed devices, as herein described, may be employed, and by connecting their latches to the latch 13 they may all be simultaneously operated by the rope 17, and for this purpose 50 the latch 13 is provided with a number of holes 18, in which the ropes connecting the several latches may be secured.

The middle compartment of the bin is intended for hay and the end compartments 55 for corn or other feed. To prevent the corn from scattering, I provide shields 19, which extend downwardly from the rear side of the bin, being hinged, as at 20, to the rear wall 11 at the lower edge thereof. The bottom 9 60 carries fingers 21, which extend upwardly into the middle compartment, the ends of the fingers being curved rearwardly, as at 22. These fingers are for the purpose of preventing the hay from sticking when the bottom 65 swings open. The shields 19 are hinged to enable them to be adjusted to suit the location of the feed-trough with respect to the bin.

I claim—

A stock-feeding device comprising a bin having a hinged bottom, a latch for holding the bottom closed, and fingers carried by said bottom and extending into the bin when the bottom is closed.

In testimony whereof I have signed my name to this specification in the presence of two subscribing witnesses.

ALBERT WADKINS HARVEY.
